ARCH SUPPORT

Eric Lyss and Alberto F. Treviño,
Pasadena, Calif.

Application July 24, 1933, Serial No. 681,930

3 Claims. (Cl. 36—71)

Our invention relates to arch supports and more particularly to certain improvements in arch supports whereby pads or cushions can be detachably and interchangeably applied thereto, and also adjusted with relation to the arch support or other insert piece for the shoe so that the pad or cushion can be positioned as may be necessary to meet a certain condition and thus give the needed comfort to the foot.

10 In order to accomplish this desired result, we have provided the body of the supporting member with a cut out or formed socket, preferably undercut around its edge, and have provided an insert pad or cushion member to be inserted into said socket, the same being held in place by the interfit established around the edge of the socket and the yielding edge of the insert piece or cushion.

20 We have also provided in combination with a support, a socket of form to receive a corresponding portion of a pad or cushion and adjustable therein to different positions radially therefrom, with an overlying pad or cushion portion to rest in different positions upon said support as may be required or convenient to give the greatest comfort to the foot of the user.

25 In order to explain our invention, we have illustrated the same on the accompanying sheet of drawing which we will now describe.

30 Figure 1 is a top plan view of an arch support showing one embodiment of our invention applied thereto, shown in light broken lines on the under side thereof;

Figure 2 is a bottom plan view thereof, showing the insert pad or cushion;

Figure 3 is a cross sectional view taken on the line 3—3 of Fig. 1;

Figure 4 is a partial longitudinal sectional view taken on line 4—4 of Fig. 1;

40 Figure 5 is a fragmentary top plan view of an arch support showing our adjustable pad or cushion; and

Figure 6 is a longitudinal sectional view taken on line 6—6 of Fig. 5.

45 Referring now in detail to the drawing, we will describe our invention as illustrated for explanatory purposes, referring first to Figs. 1 to 4 inclusive.

50 An arch support is shown, designated 10, which may be of any form desired, and these are usually composed of an inner rubber or cushion body 11, with a leather or other suitable covering 12.

On the underside of this support we have shown 55 a socket 13, of triangular shape in the present embodiment, with its edges undercut, as at 13',

and seen in the sectional view in Fig. 4, said socket extending into the body of the support.

A filler or insert pad or cushion 14 is inserted into this socket and is of the desired thickness to meet the particular requirement of the user, that is, the insert pad or cushion 14, if thicker than the body of the support, more of a cushioning effect is secured. We have shown the insert pad as somewhat thicker than the socket, which would result in raising that area of the padded 10 portion of the support. As the insert piece is of yielding material it is easily pressed into the socket provided therefor and is held therein by the overhanging, surrounding edges of said insert. Then, too, said insert piece rests upon the 15 inside sole of the shoe into which the support is placed and there is no chance of its being misplaced.

In Figs. 5 and 6, we have illustrated a means of providing an adjustable pad or cushion. This 20 is done by providing a socket in the top surface of the support. This socket is here shown as hexagonal in form and designated 15, as will be seen in the sectional view, Fig. 6. The pad or cushion member, designated 16, can be of any desired 25 form and thickness, and is provided on its under side with an extension 16', also of hexagonal form, and adapted to fit into the socket 15, for holding the pad or cushion in place. It will be seen that the pad can be turned to any desired 30 position, as will be understood from the light broken line position in Fig. 5. Thus it will be understood that the thicker portion of the pad or cushion can be adjusted around its center to any position radially as will give the most 35 comfort to the user.

We do not limit our invention to the showing here made for descriptive purposes, knowing that changes in details can be made without departing from the spirit thereof, except as we may 40 be limited by the hereto appended claims.

We claim:

1. An arch support formed of cushion material shaped to the foot to support the foot within a shoe, said cushion having an area cut out for a part only of the thickness of said cushion to form a socket having overhanging edges and an auxiliary cushioning pad cut to the same form as said socket to be seated therein, the edge of said pad being formed to underlie the overhanging edges of said pocket, whereby to be held in place therein.

2. An arch support formed of cushion material with a covering member, said covering member having a portion thereof cut out to form an un- 55

covered area and a corresponding area cut out of said cushion material to form a socket therein for a part only of the thickness of said cushion material, and an auxiliary cushioning pad in 5 shape the form of said socket and inserted therein with its edge underlying the edge of said covering member, whereby it is held in place thereby.

3. An arch support formed of cushion material 10 with a covering member, said covering member

and said cushion material having a socket cut into them for a part only of the thickness of said cushion material with overhanging edges, said edges being at angles to each other, and an auxiliary pad conforming to said socket to be seated therein and underlying the overhanging edges of said pocket to be held thereby.
